SENSITIVE DRILLING MACHINE

Martin D. Elledge, Monrovia, Calif.

Application February 3, 1958, Serial No. 713,015

8 Claims. (Cl. 77—32)

This invention relates to sensitive drilling machines and particularly to a machine for performing high speed drilling operations in the formation of very small diameter holes in hard substances. The drilling of the holes in artificial teeth formed of hard plastic or of porcelain material for reception of the securing rivets is an example of such work.

The primary object of the invention is to provide a drilling machine for forming small diameter holes in hard substances and in which the machine is characterized by being quickly adjustable and further by extreme sensitivity to the progress of a drilling tool through the work piece being drilled.

Another object of the invention is to provide a sensitive drilling machine in which the drilling tool is maintained vertically stationary while the work holding means is raised and lowered into and out of engagement with the drilling tools by means which is substantially friction free and counterbalanced wherefore, the effort expended in holding the work against the drilling tool is substantially limited to producing the required movement with the resultant increase in the degree of sensitiveness communicated to the hand of the operator.

With the foregoing objects in view, together with such additional objects and advantages as may subsequently appear, the invention resides in the parts, and in the construction, combination and arrangement of parts described, by way of example, in the following specification of certain presently preferred embodiments of the invention; reference being had to the accompanying drawings which form a part of said specification and in which drawings:

Fig. 1 is a front elevational view of a machine embodying one form of the present invention,

Fig. 2 is a right hand side elevational view of the machine shown in Fig. 1,

Fig. 3 is a top plan view of the machine shown in Fig. 1,

Fig. 4 is a fragmentary top plan view taken as looking at the work supporting portion of the machine from a position represented by the line 4—4 in Fig. 2,

Fig. 5 is a fragmentary top plan sectional view taken on the line 5—5 of Fig. 2,

Fig. 6 is an enlarged medial sectional view of the work supporting and manipulating means employed in the first embodiment of the invention, the section being taken on the line 6—6 of Fig. 2,

Fig. 7 is a fragmentary sectional view taken on the staggered line 7—7 of Fig. 6,

Fig. 8 is a fragmentary sectional top plan view taken on the line 8—8 of Fig. 6,

Fig. 9 is a fragmentary top plan view taken on the line 9—9 of Fig. 7,

Fig. 10 is a reduced scale side elevational view of a second embodiment of the invention and

Fig. 11 is a fragmentary front elevation of the device shown in Fig. 10.

The base 1 of the machine is preferably formed as

2

a casting having a top surface 2 and a depending skirt portion 3 forming the side wall of the base. At one end the base is provided with a vertical bore 4 in which a vertical tubular standard 5 is mounted. A clamp 6 operated by hand screw 7 is mounted on the standard 5 for adjustment therewith, said clamp having a laterally extending arm 8 on which a vertical axis electric motor 9 is mounted, said motor at the lower end of the shaft thereof carrying a chuck 10 for the drilling tool T.

10 Power is supplied to the motor through an electric cord 11 which enters the base, passes through a switch 12 carried by the base and thence extends upwardly through the standard 5 and then to the motor 9. The present machine is different than many drilling machines in that the

15 drill remains vertically stationary and the work to be drilled is moved upwardly into engagement with the drill by means presently to be described.

The machine is shown equipped for use for dental work such as drilling of artificial teeth for the fastening thereof into bridgework and the like. To this end the machine

20 is provided with a shallow cup element 13 having a depending stud 14 on which is mounted a spring washer 15 and a hand nut 16, the depression 17 in the upper surface of the cup serving to retain a wax or similar substance in which the tooth to be drilled is secured.

25 The spring washer, hand nut and stud afford means for detachably securing the cup 13 to the upper surface of a rearwardly extending run 18 of a work supporting member 19 disposed in the axial line of the motor shaft, said member having a depending run 20 and a forwardly extending run 21 fixed to the upper end of a rod 22 mounted for vertical reciprocation in the axial line of the motor by means presently to be described.

30 The upper run 18 of the member 19 is provided with a slot 23 extending rearwardly, said slot at the front edge of the said upper run 18 and for a short distance therefrom being only sufficiently wide to receive the stud 14. Rearwardly, said slot widens laterally so that the stud may be moved through a considerable range of positions and clamped by the nut and washer thus permitting the positioning of the cup 13 in a desired position beneath the drilling tool carried by the chuck 10. At the same time the cup and its associated nut and washer may be removed to any suitable holding means for the mounting of the tooth or teeth to be drilled in the cup, there being preferably a plurality of cups furnished with each

35 drilling machine.

40 The rod 22 is mounted for vertical adjustment in an axial bore 24 formed in a vertical cylindrical member 25 disposed below and in the axial line of the motor 9. The member 25 is mounted for reciprocation in a larger upper bushing 26 and a smaller lower bushing 27 carried, respectively, in the upper end of a cylindrical housing 28 and in a sleeve 29 fixed to and depending from a cover plate 30 which closes the lower end of the housing 28 and is removably attached thereto by screws 31, said sleeve being secured in a vertical bore 32 in the base 1 by a setscrew 33 to detachably mount the housing 28 on the base. The member 25 at one side thereof is cut away to provide a flat side 34 and a longitudinal slot 35 extends between the bore 24 and the said flat side 34. The lower end of the rod 22 is provided with a transverse threaded bore 36 which is engaged by a threaded stud 37 having a shoulder portion 38 engaging the flat side 34 to clamp the rod 22 in any desired position along the slot 35, the shank 39 of said stud extending laterally through a slot 40 in the wall of the housing 28 and externally of the housing carrying a knob portion 41 by which it may be tightened and released incident to the vertical adjustment

45 of the rod 22 along the bore 24.

50 Diametrically opposite the slot 40 therein, the wall of the housing 28 is provided with opposed laterally extend-

55

60

65

70

75

ing bosses 42 and 43 which are provided with bushings 44 and 45 affording bearing support for a shaft 46, said shaft adjacent to the member 25 carrying an eccentric 47 on which the inner race of a ball bearing 48 is mounted. The member 25 has a transverse slot 49 formed therein in which the outer race of the ball bearing 48 is received. The shaft 46 extends beyond the bearing boss 42 and carries a hand knob 50 by which it may be turned with resultant vertical movement of the member 25 being imparted by the eccentric 47. The lower end of the member 25 below the slot 49 is provided with a bore 51 in which is disposed a compression spring 52 effective to bear against the outer race of the ball bearing 48 to maintain any play between the ball bearing and the slot 49 taken up with the upper end of the slot 49 at all times bearing against the outer race of the ball bearing 48. The outer end of the boss 42 terminates in an annular flange portion 53 which is the same diameter as the shank portion of the knob 50, said shank portion 54 carrying a set of graduations 55 which register with an indicia line 56 on the flange 53. The graduations may be for any desired amounts of vertical movement. In the illustrated embodiment of the invention, the graduations indicate millimeters of vertical movement of the member 25 and consequently of the work holding cup mounted thereon, it being understood that due to the movement of the eccentric the graduations will be spaced at varying distances apart so that they will indicate uniform increments of vertical movement.

The lower end of the member 25 is reduced in diameter to a short substantially square portion 57 which is conveniently initially formed as a threaded portion, thereafter having the sides cut away to form a portion of square cross section of such size that the threads remain on the corners. A bowed leaf spring 58 extends diametrically across the housing 24 and has its opposite ends attached to the housing side walls by screws 59 and nut 60, said spring at its mid-length having a square opening 61 through which the said square portion 57 of the member 25 extends. A nut 62 and washer 63 engaging the threads on the corners of the square portion 57 serve to clamp it against the shoulder 64 formed by the juncture of the square portion 57 and the larger circular portion of the member 25. Below the square portion 57 the member 25 extends in a small diameter bearing portion 65 which slidably engages the bushing 27. The spring 58 is initially biased to tend to move the member 25 and the work supporting means carried thereby downwardly to the extent permitted by the rotation of the shaft 46 to a point bringing the high point of the eccentric extending directly downwardly. The hand knob 50 on the shaft 46 is normally maintained adjusted so that the zero line on the graduations on the hand knob is in registry with the indicia mark on the flange 53, the set screw 50' which secures the hand knob 50 to the shaft 46 being loosened and then retightened to achieve this setting.

In a representative use of the device a cup 13 having the work to be drilled is mounted on the work holding means and secured by the nut 16. A drill of the proper size is placed in the chuck 10 and the motor bracket is adjusted downwardly if necessary on the standard 5 until the drill is close to the work. The cup is then adjusted laterally until the point at which the drill is to enter the work is directly in line with the drill, the distance between the drill and the surface of the work being as little as possible. Alternatively, the drill and motor can be brought downwardly for a coarse adjustment and a finer adjustment of the work toward the drill can be achieved by the upward adjustment of the member 22 by use of the clamping stud 39 operated by the hand knob 41. Also, if desired, the lateral adjustment may be achieved by movement of the bracket arm 8 about the standard 5. Having thus aligned the drill with the work the work is moved up against the drill by turning the hand knob 50

5 using whatever pressure, either constant or intermittent, and using whatever lubricant, if any, is necessary.

10 The illustrated embodiment of the invention is arranged to form holes not exceeding 5 millimeters in depth but this is merely a function of the throw of the eccentric 47, it being evident that greater or lesser throws might be employed for individual uses. When the hole is completed, the work is either removed if it is a completion of a piece being drilled or the work or the drill head may be shifted laterally for the formation of another drilled hole as the nature of the work may require. It is particularly to be noted that due to the fact that the ball bearing is employed, and that the movement of the work supporting means in the drilling operation is opposed to the action of the spring 58, the feeling of the movement of the drill through the work can be accurately detected by the hand knob 50.

15 Referring to the second embodiment of the invention shown in Fig. 10, the base standard and motor are generally similar to that in the first described form, and therefore the same numbers have been added with the addition of the exponent a . The work supporting means comprises a bracket 66 having a slot formed therein similar to the slot 23 in the first form of the invention for securing the work supporting means comprising a cup, stud, washer and nut which may be identical with that shown in the first form of the invention. The bracket terminates in a supporting portion 67 having parallel horizontal upper and lower faces to which the ends of leaf springs 68, 68 are attached by rivets, or the like. The opposite ends of these leaf springs are similarly attached to a corresponding lug 69 carried by a clamp member 70 surrounding the standard 5a and secured in vertical adjusted position thereon by a screw 71. The under face of the clamp 70 carries a downwardly and forwardly extending bracket member 72 secured thereto by screws 73, said bracket terminating beneath the end of the hand nut 16a and affording bearing support for a shaft 74 which at one end is provided with an eccentric 75 engaging the under surface of the nut 16a and at its other end carries a hand wheel or knob 76. As in the first embodiment of the invention, the springs 68, 68 normally apply a substantial downward bias on the bracket 66 and thereby maintain the lower face of the nut 16a in constant contact with the surface of the eccentric 75. The hand wheel carries an indicia bearing surface 77 marked off in graduations which register with a reference mark on an arm mounted on the journal portion of the bracket 72 adjacent the end at which the hand wheel 76 is located, the said graduations being spaced to indicate uniform increments of upward movement of the work support by the rotation of the eccentric 75.

20 This embodiment of the invention is equally satisfactory for most of the operations for which the first described form may be used although it is not quite as accurate in that the spring 68, 68 while giving the bracket 66 a generally directly upward movement similar to a parallel rule type of movement, do impart a slight amount of rock to this bracket and consequently to the work. The difference is a matter of perhaps one or two-thousandths of an inch and unless that difference is critical this form of the invention is just as satisfactory as the first form of the invention and in fact is somewhat cheaper to produce.

25 Thus there has been provided a sensitive drilling machine for drilling holes of very small size and of limited depth in very hard substances and in which the objectives of the invention are realized in practice.

30 The foregoing description has disclosed, by way of example, certain presently preferred embodiments of the invention but it will be understood that the invention is not to be deemed to be limited to the forms thus disclosed and that the invention embraces all such changes and modifications in the parts, and in the construction,

combination and arrangement of parts as shall come within the purview of the appended claims.

I claim:

1. In a drilling machine, a base, a standard rising from said base, a vertical axis shaft and driving means therefor journaled on said standard at one side thereof, said shaft having a drill holding chuck at the lower end thereof, a work manipulating means disposed beneath said drill and including a member mounted for vertical movement in a line which is substantially equal in distance from said standard as is the axial line of said shaft, a work holding means detachably mounted on said work manipulating means, spring means constantly imposing a bias on said work manipulating means tending to move said work manipulating means downwardly, and manually operable means for moving said member upwardly comprising a horizontal shaft having a hand wheel at one end thereof and eccentric means at the other end thereof engagable with said work manipulating means and effective upon rotation of said shaft by said hand wheel through a half revolution to move said work manipulating means upwardly in opposition to the bias imposed by said spring means towards a drill carried by said chuck.

2. A drilling machine as claimed in claim 1 in which said work manipulating means and said horizontal shaft are mounted on said base.

3. A drilling machine as claimed in claim 1 in which said work manipulating means and said horizontal shaft are mounted on said standard with capacity for adjustment longitudinally of said standard.

4. In a drilling machine, a base, a standard rising from said base, a vertical axis motor carried by a bracket mounted on said standard and having a drill holding chuck at the lower end of the shaft of said motor, said shaft being disposed laterally of said standard, a work manipulating means carried by said base comprising a member mounted for vertical movement in a line which is substantially equal in distance from said standard as the axial line of the motor, a rod carried by said member and carrying a work holding means at the upper end thereof, spring means constantly imposing a bias tending to move said member downwardly, and manually operable means for moving said member upwardly comprising a horizontal shaft carrying a hand wheel at one end thereof and an eccentric means at the other end thereof engaging said member, said eccentric means being effective upon rotation of said shaft through a half revolution to move said work manipulating means upwardly against the bias of said spring means with resultant engagement of a work piece carried by said work holding means by a drill in said chuck.

5. A drilling machine as claimed in claim 4 in which said rod is vertically adjustable on said member.

6. A drilling machine as claimed in claim 4 in which said base carries a housing having aligned bearings in which said member is vertically reciprocable and other bearings in which said horizontal shaft is journaled.

5 7. A drilling machine comprising a base, a standard rising from said base, a bracket projecting laterally from said standard and overhanging said base, a vertical axis shaft journaled in said bracket and held against relative endwise movement therein, said shaft having a drill holding chuck on the lower end thereof, a work holding means disposed below said shaft including manually operable devices for moving said work holding means upwardly toward a drill held in said chuck, said work holding means including a bracket member, a shallow cup detachably secured to said bracket member adapted to support a work piece adhesively mounted thereon, and means detachably securing said cup to said bracket in an infinitely variable range of positions in a horizontal plane defined by said bracket member.

10 8. In a drilling machine a base, a standard rising from said base, a bracket mounted on said standard and projecting laterally therefrom a vertical axis motor mounted on said standard and overhanging said base a drill chuck on the lower end of the motor shaft, work holding and manipulating device carried by said standard adjacent to said base and comprising a bracket fixed to said standard, a pair of vertically spaced, horizontally parallel leaf spring elements each having one end thereof attached to said last-named bracket, means for supporting a detachable work holding means secured to the opposite ends of said leaf spring elements, a bearing bracket for a horizontal shaft projecting laterally from said standard below said second named bracket, a horizontal shaft mounted in said shaft carrying bracket and having a hand wheel 15 on one end thereof and an eccentric member on the other end thereof, a work holding means detachably mounted on said supporting means and including a clamp screw element disposed above and in contact with said eccentric member whereby upon rotation of said eccentric member through a half revolution said supporting means and the work holding means mounted thereon will be elevated against the bias of said spring element in a substantially vertical line with resultant engagement of a work piece carried by said work holding means with a 20 drill mounted in said chuck.
